INVENTOR:

Palmie Spalding

United States Patent Office.

PALMER SPALDING, OF CHICAGO, ILLINOIS, ASSIGNOR TO HIMSELF, WILLIAM SPALDING, AND TRUMAN D. SPALDING.

Letters Patent No. 95,159, dated September 21, 1869.

IMPROVED PINCH-BAR.

The Schedule referred to in these Letters Patent and making part of the same.

To all whom it may concern:

Be it known that I, PALMER SPALDING, of the city of Chicago, in the county of Cook, and State of Illinois, have invented a new and improved Pinch-Bar or lever, in combination with fulcrum; and I do hereby declare that the following is a full and exact description of the construction and operation of the same; reference being had to the annexed drawings, making a part of this specification.

I construct my improved lever with its own fulcrum, which I call a pinch-bar, of the usual sizes of ordinary levers in use, but for running cars upon their track or elsewhere, and safes, and other heavy bodies, I prefer a bar made of wrought-iron or steel, five feet in length, one and one-quarter inch square, tapering toward the upper end, like ordinary bars or levers now in use.

At the lower end of the lever, I make a peculiarly-shaped face, furnishing, as it were, a cam upon the upper side of the bar; and on the under side of the bar I make a heel or fulcrum, pointed and notched, as

shown in the drawings, and of steel, so that the point of the heel will be about three inches in a straight line from the points of the bar.

The operation and utility of the bar, as improved by me, are exemplified when applied to the moving of railroad-cars upon their track, the notches biting the track and furnishing the point on which the lever turns, and the face of the bar operating against the wheel. Immense power, with my pinch-bar, by one man, may thus be exerted.

What I claim, and desire to secure by Letters Patent, is—

A pinch-bar, having its short arm with a fixed convex face, and its heel or fulcrum formed with teeth, as and for the purposes hereinbefore set forth.

PALMER SPALDING.
